UNITED STATES PATENT OFFICE.

GURDON PENDLETON, JR., OF CARBONDALE, PENNSYLVANIA, ASSIGNOR TO
THE PENDLETON MANUFACTURING COMPANY, OF SAME PLACE.

DESIGN FOR A JAR.

SPECIFICATION forming part of Design No. 27,381, dated July 20, 1897.

Application filed June 16, 1897. Serial No. 641,068. Term of patent 14 years.

To all whom it may concern:

Be it known that I, GURDON PENDLETON, Jr., a citizen of the United States, residing in Carbondale, county of Lackawanna, and 5 State of Pennsylvania, have invented a new and useful Design for a Package-Jar; and I do hereby declare that the following is a full, clear, and exact description of the same.

Reference is to be had to the accompanying 10 drawing, forming a part of this specification, which represents a package-jar embodying my novel design.

The leading feature of my design consists 15 of a cylindrical body surrounded by milled or corrugated bands.

In the accompanying representation of my design the body A of the jar is supposed to be of glass, is cylindrical, and is surrounded

at its top and bottom by integral and parallel bands B and C, respectively, raised slightly 20 above the surface of the body and having a vertical milling or corrugations D.

E is a cover for the jar, which may be of any suitable design and forms no part of the 25 design I now claim.

Having thus described the general character of my design and illustrated it by an example, I claim as my invention—

The design for a package-jar substantially 30 as herein shown and described.

In testimony whereof I have hereunto set my hand the 12th day of March, 1897.

GURDON PENDLETON, JR.

In presence of—

HERMAN MEYER,
CHESTER HIGGINS.
